United States Patent Office

Des. 203,614
Patented Feb. 1, 1966

203,614

BREAD TRAY OR THE LIKE

John L. Czasonis, Plainville, Conn., assignor to The International Silver Company, Meriden, Conn., a corporation of Connecticut

Filed Mar. 8, 1965, Ser. No. 84,147

Term of patent 14 years

(Cl. D44—10)

FIG.1.

FIG.2.

FIG. 1 is a top plan view of a bread tray or the like, showing my new design.

FIG. 2 is a side elevational view.

FIG. 3 is a bottom plan view.

FIG. 4 is a cross sectional view taken on line 4-4 of FIG. 1 and

FIG. 5 is a sectional view taken on line 5-5 of FIG. 1.

I claim:

The ornamental design for a bread tray or the like, as shown.
